BY

UNITED STATES PATENT OFFICE.

CHARLES F. NOFTZGER, OF CHICAGO, ILLINOIS.

LAUNDRY DRIER.

Application filed July 30, 1926. Serial No. 125,944.

The main objects of this invention are:

First, to provide an improved laundry drier by means of which laundry may be quickly dried with a minimum of wear and tear upon the laundry.

Second, to provide an improved laundry drier which is adapted for handling a quantity of clothes en masse without their becoming tangled or knotted together.

Third, to provide an improved laundry drier which is of very large capacity and one in which the clothes are left in a fluffy unwrinkled condition, it being possible to evenly dry a quantity of clothes to the desired condition for ironing or to a completely dried condition, as may be desired.

Objects pertaining to details and economies of construction and operation of my invention will definitely appear from the detailed description to follow. The invention is clearly defined and pointed out in the claims.

A structure embodying the features of my invention is clearly illustrated in the accompanying drawing forming a part of this application, in which:

Fig. 1 is a front elevation of a structure embodying the features of my invention, a portion of the housing being broken away to show the parts within.

Fig. 2 is a vertical section on a line corresponding to line 2—2 of Fig. 3, parts being shown in full lines for convenience in illustration.

Fig. 3 is a horizontal section on a line corresponding to line 3—3 of Figs. 1 and 2.

Referring to the drawing, the supporting frame in the embodiment illustrated comprises a base casting 1 supported in an elevated position by the legs 2. On this base is a housing 3 for parts of the mechanism and on this is supported a drying chamber 4. This drying chamber is preferably cylindrical as illustrated and open at the top for the passage of air therethrough, a screen 5 being provided to prevent any of the articles to be dried being carried through by the current or blast of air.

Within the housing 3 is a framework 6 having spiders 7 at the top supporting the vertical bearing 8 for the reciprocating rod 9. On this rod 9 is a spider-like frame 10

supporting the screen or foraminated bottom 11, the bottom being thus supported for vertically reciprocating movement. The flexible extension 12 is secured to the edge of the bottom and the outer edge of this extension is secured to the side of the drying chamber.

In the bottom of the housing 3 is a fan 13 which is carried by the vertical shaft 14 mounted on the bearing 15 in the base casting 1 and on a suitable bearing in the yoke-like hanger 16 depending from this casting. This hanger also provides a support for the inner end of the driving shaft 17 which is connected by the beveled gears 18 to the shaft 14.

In the embodiment illustrated the foraminated bottom is reciprocated by a mechanism comprising the lever 19 which is pivoted at 20 on the frame 6 and engaged by a crank pin 21 on the gear 22. This gear is driven from a worm 23 on a shaft 24 arranged horizontally in suitable bearings on the frame 6 and connected by the gears 25 and 27 to the fan shaft. With this arrangement the bottom is intermittently reciprocated, being raised and allowed to fall, thus in effect tossing the clothes upwardly in the current of air produced by the fan or other suitable air blast means. This loosens the clothes so that they are more readily picked up and held in suspension by the blast of air.

As a further means for agitating or tumbling the clothes I provide a movable baffle or deflector for the air current consisting in the embodiment illustrated of a rotary baffle member 28 consisting of a pair of segmental baffle wings carried by the hub 29 which rests upon the hub of the fan, it being, however, rotatable independently thereof. These baffle wings have downturned flanges 30 on corresponding edges so that the blast of air rotates the baffle by means slower than the speed of the fan, the effect being to deflect the blast of air by obstructing its passage so that it is delivered with an uneven force to the laundry, thereby tending to tumble and turn the laundry which is held more or less in suspension by the blast of air, at least as soon as the clothes become partially dry.

The air delivered may be heated and in the embodiment illustrated I show a heating

coil 31, although suitable means for heating the air may be provided as desired.

I preferably provide the drying chamber with a side door 32 for the introduction and removal of the laundry and a window 33 for facilitating the determination of the condition of the articles being dried without opening the door. The housing 3 has a side door 34.

10 With the parts thus arranged I provide a structure which is of very large capacity and is highly efficient, the laundry being dried with a minimum of wear and tear and coming from the drier in a fluffy wholesome 15 condition.

I have illustrated a simple and practical embodiment of my improvements and it is believed that this will enable those skilled in the art to which my invention relates to 20 embody or adapt the same as may be desired, and I have therefore not attempted to illustrate and describe various modifications and adaptations which I contemplate.

Having thus described my invention what 25 I claim as new and desire to secure by Letters Patent is:

1. In a laundry drier, the combination of an upright cylindrical drying chamber open at the top for the discharge of air, a vertically reciprocating foraminated bottom for 30 said drying chamber, a flexible extension connecting the edges of said bottom to the walls of the drying chamber permitting its vertical movement, means for reciprocating said bottom with a stroke of varying speed, and a fan disposed below said bottom to deliver a blast of air therethrough.

2. In a laundry drier, the combination of a drying chamber open for the discharge 40 of air, a vertically reciprocating foraminated bottom for said drying chamber, a fan disposed below said bottom to deliver a current of air therethrough, and a baffle rotatably mounted between said fan and bottom.

45 3. In a laundry drier, the combination of a drying chamber open for the passage of air therethrough, a vertically reciprocating foraminated bottom, a flexible extension connecting the edges of said bottom to the walls 50 of the drying chamber, means for reciprocating said bottom, and means for delivering a blast of air through said bottom.

4. In a laundry drier, the combination of a drying chamber open for the passage of air therethrough, a vertically reciprocating foraminated bottom, means for reciprocating said bottom, means for delivering a blast of air through said bottom, and a movable baffle operatively associated with the air 60 blast to vary the delivery thereof.

5. In a laundry drier, the combination of a drying chamber open for the passage of air therethrough and provided with a foraminated bottom, a fan disposed below said 65 bottom to discharge a blast of air there-

through, and a rotating baffle interposed between the fan and said bottom and provided with segmental baffle wings having downturned flanges whereby the baffle is rotated by the air delivered by the fan.

6. In a laundry drier, the combination of a drying chamber open for the passage of air therethrough and provided with a foraminated bottom, a fan disposed below said bottom to discharge a blast of air therethrough, and a rotating baffle interposed between the fan and said bottom.

7. In a laundry drier, the combination of a drying chamber open for the circulation of air therethrough and provided with a foraminated bottom, means for delivering a current of air therethrough, and a rotating baffle interposed in said air current, all co-acting for the purpose specified.

8. In a laundry drier, the combination of a drying chamber open for the passage of air therethrough, means for delivering a blast of air upwardly through said chamber, and a vertically reciprocating foraminated bottom member disposed in said chamber above said air delivery means and operatively connected to the walls of the chamber to permit reciprocation and compel the passage of air through the bottom member, said chamber being unobstructed above the bottom member permitting free tumbling movement of the laundry under the combined action of said bottom member and the blast of air.

9. In a laundry drier, the combination of a drying chamber open for the passage of air therethrough, means for delivering a blast of air upwardly through said chamber, and a vertically reciprocating laundry supporting and tossing member open to permit free passage of the blast of air therethrough disposed above said air delivery means and operatively associated with the walls of the chamber to compel the passage of the air through said member, said chamber being unobstructed above said member permitting free tumbling movement of the laundry under the combined action of said supporting and tossing member and the blast of air.

10. In a laundry drier, the combination of a drying chamber open for the passage of air therethrough, means for delivering a blast of air upwardly through said chamber, a laundry supporting and tossing member open to permit free passage of the blast of air therethrough disposed above said air delivery means and movably associated with the walls of the chamber to compel the passage of air through said member, and means for vertically reciprocating said laundry supporting and tossing member.

11. In a laundry drier, the combination of a drying chamber open for the passage of air therethrough, means for delivering a blast of air upwardly through said chamber,

and a vertically reciprocating laundry supporting and tossing member open to permit free passage of the blast of air therethrough disposed above said air delivery means and 5 flexibly connected to the walls of the chamber to compel the passage of air through said member.

12. In a laundry drier, the combination of a delivery chamber open for the passage of 10 air therethrough, means for delivering a blast of air upwardly through the laundry within said delivery chamber, and a laundry tossing means within said chamber operatively associated with the walls of the chamber 15 so that the blast of air is compelled to pass through said tossing means.

13. In a laundry drier, the combination of a drying chamber open for the circulation of air therethrough, means for delivering a 20 blast of air upwardly through said drying chamber, a vertically reciprocating bottom member open to permit the passage of air therethrough operatively associated with the 25 walls of the chamber to permit its reciprocation and compel the passage of the air through said bottom, and means for reciprocating said bottom with a quick downward return movement, said drying chamber being unobstructed above said bottom to permit 30 free movement of the articles being dried under the combined tossing action of the reciprocating bottom and the blast of air.

14. In a laundry drier, the combination of a drying chamber open for the circulation 35 of air therethrough, means for delivering a blast of air upwardly through said drying chamber, a vertically reciprocating bottom member open to permit the passage of air therethrough operatively associated with the 40 walls of the chamber to permit its reciprocation and compel the passage of the air through said bottom, and means for reciprocating said bottom member with a substan-

tial stroke in the direction of the current of air.

15. In a laundry drier, the combination of a drying chamber open for the circulation of air therethrough, means for delivering a blast of air upwardly through said drying chamber, a vertically reciprocating bottom 50 member open to permit the passage of air therethrough operatively associated with the walls of the chamber to permit its reciprocation and compel the passage of the air through said bottom, and means for reciprocating said bottom member in the path of the blast of air with a relatively rapid movement against the blast of air.

16. In a laundry drier, the combination of a drying chamber open for the circulation 60 of air therethrough, means for delivering a blast or current of air upwardly through said drying chamber, a vertically reciprocating foraminated bottom operatively associated with the walls of the chamber above 65 said air delivery means to permit its reciprocation and compel the passage of the air therethrough, and means for reciprocating said bottom with a quick upward tossing movement.

17. In a laundry drier, the combination of a drying chamber open for the circulation of air therethrough, means for delivering a blast or current of air upwardly through said drying chamber, a vertically reciprocating 70 laundry supporting and tossing member open to permit the free passage of the air therethrough disposed above said air delivery means and operatively associated with the walls of the chamber to compel the passage 75 of air through the supporting member, and means for vertically reciprocating said member with a quick upward tossing movement.

In witness whereof I have hereunto set my hand.

CHARLES F. NOFTZGER.
